INDICATOR DIAL

Frederick B. Brand, Hollis, N. Y., assignor to Control Instrument Company, Inc., Brooklyn, N. Y., a corporation of New York

Application February 9, 1944, Serial No. 521,705

3 Claims. (Cl. 116—129)

This invention relates to improvements in indicators and has particular reference to a dial construction such as may be employed on navigational, fire control, and other like instruments.

As is well-known, dials for use on instruments of the above character are illuminated and, heretofore, it has been customary to make such dials of a light material such as aluminum with the outer edge of the dial or disc formed with perforations or slots which are filled with a translucent substance to provide the index markings that are illuminated from below or in back of the dial. Due to the present critical nature of aluminum, it has been necessary to employ some other material in the manufacture of these dials. The best substitute at present known is a plastic having good translucent characteristics and which readily lends itself to engraving operations, but the difficulty experienced with this material, especially when used to make larger size dials, is that of warpage.

According to the present invention, the above difficulty is overcome by the provision of a dial of improved construction the elements of which may be easily assembled and adapted for mounting upon a hub when the dial is to be coupled to a shaft, and wherein stiffening plates forming a part of the dial have their peripheral portions secured to the index ring of said dial and their central portions engaging each other in such manner that the possibility of warping is practically eliminated and the stiffening components of the dial will impart a minimum moment of inertia.

The inventive idea involved is capable of receiving a variety of mechanical expressions, one of which for purposes of illustration is shown in the accompanying drawing; but it is to be expressly understood that said drawing is used only to describe the invention as a whole and not to define the limits thereof, reference being had to the appended claims for this purpose.

In the drawing—

Fig. 1 is a front elevation of a dial constructed in accordance with the invention.

Fig. 2 is an elevational view, partly broken away, of the back or under side of the dial.

Fig. 3 is a transverse section through the center of the dial.

Fig. 4 is a detailed sectional view through one of the stiffening or reinforcing plates before being assembled in the dial and.

Fig. 5 is an enlarged sectional view of a portion of the hub assembly.

The preferred form of the invention is shown

mounted upon a hub 5, as when the dial is to be coupled to the shaft of an instrument, and said hub is provided with an annular flange 6 slightly offset from the outer end of the hub to provide an annular shoulder 7.

The dial comprises outer and inner stiffening plates 8 and 9, respectively, which are adapted to be mounted upon the flange 6 of said hub and abutted against the shoulder 7 thereof so as to 10 retain said plates in concentric relation to the axis of the dial. The inner or central portion of the plates 8 and 9 contact each other and said plates are held in place by a central clamping disc 10 which overlies the inner portion of 15 said plate 8 and which is secured to the hub 5 by screws 11. The outer plate 8 is flat throughout its area while the inner plate 9, made of a suitable resilient material, is inwardly offset at 12 to provide an intermediate portion 13 thereof which inclines outwardly toward the plate 8 when the parts are in assembled position. Before the 20 plate 9 is assembled with other elements of the dial, as shown in Fig. 4, the peripheral portion 14 thereof, which is slightly bent so as to be at an angle to the portion 13 and in a plane parallel to the central portion of said plate, is slightly 25 offset inwardly with respect to the latter portion so that when the stiffening plates are brought together and assembled, as in Fig. 3, said plate 9 will be flexed from its normal condition and thus placed under tension to cause its central or hub portion to exert outward pressure against the adjacent central portion of the plate 8, thereby increasing the stiffening effect of the combined 30 plates. A series of openings 15 may be provided in the portion 13 of the plate 9 so as to materially lighten said plate and economize in the amount of material used.

To complete the dial, there is provided an index 35 ring 16 of narrow width relative to the over-all diameter of the dial, and which may be made of a plastic having translucent characteristics so that when the outer surface is coated with a masking paint in accordance with standard practice and the index markings 17 are engraved about its periphery, these markings will be clearly visible when the dial is illuminated from the back or underneath side thereof. Said ring 16 has its inner portion disposed between the plates 40 8 and 9 and is secured to said plates by any suitable means such as a series of rivets 18 which also accomplish the purpose of fixing the outer portions of the two plates relative to each other.

From the foregoing it will be obvious that the 45 elements of the dial may be easily and quickly

assembled and that when so assembled the plates 8 and 9 will combine to rigidly maintain the index ring in position and prevent any warping of the dial and impart thereto a minimum moment of inertia.

What is claimed is:

1. In an instrument dial adapted for mounting upon a hub when coupling said dial to a shaft, said dial comprising an index ring capable of being concentrically arranged about said hub, stiffening plates having peripheral portions engaging said ring and their central portions engaging each other, one of said plates being spring biased so as to exert pressure against the other plate, and means to secure the peripheral portions of said plates to said ring.

2. In an instrument dial adapted for mounting upon a hub when coupling the dial to a shaft, said dial comprising an index ring capable of being concentrically arranged about said hub, stiffening plates having peripheral portions engaging said ring and their central portions freely

tions and the plane of the latter portion of said plate, before assembly of the plates, being laterally offset from the plane of said central portion, and means to secure together said ring and the peripheral portions of said plates.

3. In an instrument dial, a hub having a flange, a pair of stiffening plates having central abutting portions one of which rests against said flange, a central clamping disc secured to said hub in overlying engagement with the abutting portion of the other of said plates, the first named plate having an intermediate portion offset from its central portion and extending outwardly in a peripheral direction therefrom and inclined towards said other plate and further having an outer portion which, before assembly of said plates, is in a plane parallel to but offset from said central portion so that the latter will exert outward pressure against the central portion of said other plate, an index ring positioned between said plates, and means to secure the peripheral portions of said plates to said ring and to each other.
